UNITED STATES PATENT OFFICE

2,429,661

DETACHABLE COIN DISPENSER FOR
LADIES' HANDBAGS

Lilly Amsterdam, Newark, N. J.

Application November 7, 1945, Serial No. 627,118

2 Claims. (Cl. 150—37)

1

This invention relates to an improved coin dispensing attachment for ladies' pocket books, and one of its objects is to provide a holder having a series of individually operative coin receptacles arranged in a row, and means for securing the holder to the edge of the wall of a lady's hand bag or purse, so that the usual closure flap of the hand bag or purse will normally conceal the coin holder.

The invention, in particular, is designed to provide a simple attachment, which may be fitted to any used or new hand bag or purse, by a relatively inexpensive operation, which will in no way change the styling or general construction of the hand bag or purse.

With the above and other objects in view, the invention comprises certain new and useful combinations, constructions and arrangements of parts, clearly described in the following specification, and fully illustrated in the accompanying drawings, in which:

Fig. 1 is a perspective view, showing the closure flap of the hand bag in open position to expose the attached coin holder.

Fig. 2 is an enlarged side elevation of the coin holder.

Fig. 3 is a vertical sectional view, taken on line 3—3 of Fig. 2, looking in the direction of the arrows.

Referring to the accompanying drawings, which illustrate the practical embodiment of my invention, 5 designates a conventional lady's hand bag, having the usual front wall 6, the rear wall 7, and the closure flap 8, which is hinged along the upper edge of the rear wall, and provided with the button snap element 9 to engage the cooperating button snap element 9a of the front wall 6.

On the front wall 6 I attach my improved coin dispensing holder. This holder includes a U-shaped plate 10, which thus provides a short front wall 10a and a wider rear wall 10b, and a connecting bend 10c, which holds the walls 10a and 10b in spaced parallel relation to each other. This U-shaped plate or base is mounted astride the front wall 6, so that the narrow wall 10a will bear against the front side of the front wall 6, and the wider wall 10b will bear against the rear side of the front wall 6.

The wider wall 10b is secured to the front wall 6 of the hand bag by means of button snap elements 11 and 12, secured to the walls 6 and 10b, respectively. By detaching the wide wall 10b from the front wall 6, the entire coin dispensing holder may be detached from the hand bag.

2

The front and narrow wall 10a is equipped with a horizontal row of coin holding pockets 13, arranged between the opposing walls 14 and 15 of the case 16. Between these walls 14 and 15 flanged plungers or followers 17 are arranged, and are engaged by the coil springs 18, one of which is shown in Fig. 3, and pressed against the transversely slotted stop plate 19, the individual slots of which are smaller than the follower discs or cups 17, and narrower than the coins which are held between the follower discs and the stop plate 19.

The stop plate slots 19a open through one side of the plate, so that the coins may be withdrawn from the holder by a sliding lateral motion.

Normally the closure flap of the hand bag completely conceals the coin dispensing holder from observation, and when the user wishes to find a five cent piece or coin, or a ten cent piece or coin, the closure flap is raised, and the proper coin is removed.

The arrangement of the coin dispensing holder as shown provides for two pockets 13a for the ten cent pieces or coins, and the balance or four pockets 13 are used for five cent coins. These two coins cover the requirements for operating pay station telephones, or riding on street cars or buses.

Any other arrangement of the coin holder may be made, so as to provide for dispensing coins of twenty-five cent value, in addition to the five and ten cent coins.

It is not necessary for the user of the hand bag to lift the closure flap so as to entirely expose the coin holder, as the hand may be extended under the closure flap, after it has been separated from the front wall 6, and the required coin or coins removed, after which the closure flap may be secured in closed position.

It is understood that various changes in the details of construction, their arrangement and combination, may be made, and that various materials may be used for the construction of the holder, within the scope of the invention, as defined by the claims hereof.

Having described the invention, I claim as new:

1. The combination with a lady's hand bag having a front wall and a closure flap folding over and against the front wall, of a coin dispensing holder having a detachable U-shaped base straddling the upper edge of the front wall, and a series of spring pressed coin dispensing members supported on said base outwardly of the front wall and normally concealed by the closure flap.

55

2. The combination with a lady's hand bag having a front wall and a closure flap having detachable connection with the front wall, of a coin dispensing holder having a U-shaped base mounted astride the upper edge of the front wall, said base having a wide wall to engage the rear side of the front wall and a narrow wall to engage the front side of the front wall, a connector at each end of the wide wall for holding said base detachably on the said front wall, and a series of spring pressed coin dispensing retainers mounted on the narrow wall of said base and normally concealed by the closure flap of said hand bag.
